CLAIM

The ornamental design for a candlestick, as shown and described.

DESCRIPTION

FIG. 1 is a perspective view of the candlestick showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view of thereof; and,

FIG. 7 is a bottom plan view of thereof.

The broken lines in the drawings are for the purpose of illustrating two heart-shaped portions on top of the candlestick and form no part of the claimed design.

1 Claim, 7 Drawing Sheets
